VACUUM TUBE

Original Filed Nov. 2, 1915

Inventor:
Harold De Forest Arnold.
by *J.S. Roberts* Atty.

UNITED STATES PATENT OFFICE

HAROLD D. ARNOLD, OF MAPLEWOOD, NEW JERSEY, ASSIGNOR TO WESTERN ELECTRIC COMPANY, INCORPORATED, OF NEW YORK, N. Y., A CORPORATION OF NEW YORK

VACUUM TUBE

Original application filed November 2, 1915, Serial No. 59,210. Divided and this application filed February 3, 1919. Serial No. 274,751.

The invention relates to electron discharge devices such as may be employed for repeaters, amplifiers, detectors, etc.

These discharge devices commonly employ cathode and anode electrodes, the space current between which is controlled by a grid electrode. The grid or control electrode is usually interposed between the cathode and the anode.

10 The objects of this invention are to improve the construction of the grid electrode and to provide an improved means for mounting the electrodes within the evacuated envelope.

15 According to the invention a double anode is provided comprising a pair of plates equally spaced on opposite sides of the cathode. The grid is likewise double and is formed of a pair of inverted U-shaped end frames 20 connected at top and bottom by relatively heavy wires and at intermediate points on the depending portions by relatively fine wires forming the grid surfaces. The grid surfaces are interposed between the cathode and 25 the corresponding anode surfaces. All of the electrodes are supported in position on the press or squash by means of a laterally disposed glass arbor.

This application is a division of application Serial No. 59,210, filed November 2, 1915.

The invention will be explained in the following detailed description and claims taken in connection with the accompanying drawing, which shows in perspective, partly 35 broken away, a vacuum tube embodying the invention.

The vacuum tube 10 has sealed into its base a press 11 in which are sealed the leading-in wires for the electrodes. Extending laterally and then upwardly from the press 40 is a glass rod or arbor 12. The filamentary cathode 13 is supported at its upper end from the arbor 12 by means of wires 14, and at its lower end is connected to its external circuit by means of wires 15, its mid-point being further supported from the press by wire 16. The grid electrode indicated at 17 comprises 45 the inverted U-shaped frames 18 which are rigidly connected at their upper and lower ends by wires 19. The depending side frames

thus formed have connected thereacross the wires 20 which as shown are smaller than the wires forming the frames 18. The grid 17 is supported at its upper end from the arbor 12 by the wire 21 and at its lower end from the press by the wire 22, which serves also as a connection to the corresponding leading-in wire. The anode comprises two plates 23 connected by a wire 24, and is supported from the arbor 12 by the wire 25 and from the press 55 by the wire 26, the latter being connected to the leading-in wire for the anode.

As illustrated the vacuum tube 10 is connected to a repeater circuit, shown conventionally at A. The input from a source of electric signals (not shown) is received through a transformer 27, and the output of the repeater is transmitted through a transformer 28. The secondary of the input transformer is shunted by a high resistance 29. 60 Certain features of the repeater circuit shown herein are described and claimed in my Patent No. 1,448,550 of March 13, 1923.

It is to be understood that while the preferred embodiment of the invention has been 75 illustrated, the invention is not limited to the exact form shown but includes variations thereof within the scope of the appended claims.

What is claimed is:

1. A vacuum tube device comprising an arbor, a cathode, anode surfaces on opposite sides of said cathode and a unitary double grid electrode having a plurality of substantially parallel grid surfaces, each of which lies between said cathode and one of said anode surfaces, a rigid metallic member connecting said anode surfaces, and supporting connections from said arbor to each of said electrodes. 80

2. A grid electrode for vacuum tubes comprising two U-shaped frames and a plurality of members connected at spaced intervals therebetween. 85

3. A grid electrode for vacuum tubes comprising two U-shaped frames and a plurality of members connected at spaced intervals therebetween, certain of said members being smaller in cross-section than the members composing said frames. 90

4. A grid electrode for vacuum tubes comprising two U-shaped frames connected at their corresponding ends by rigid bars and connected intermediate their ends by relatively small bars.
5. A grid electrode for vacuum tubes comprising a pair of frames, a plurality of wires supported by each of said frames, means rigidly connecting said frames together, and means for supporting said electrode.
6. A vacuum tube device comprising a column, a pair of spaced plates forming an anode, a cathode therebetween, a double grid electrode embracing said cathode, and a single arbor substantially coextensive with said electrodes carried by said column, all of said electrodes being supported from said arbor.
7. A vacuum tube device comprising a neck, a double anode, a double grid electrode within said anode, a cathode within said grid electrode, a single arbor substantially coextensive with said electrodes extending from said neck, and connections whereby said electrodes are supported solely by said neck and arbor.
8. A vacuum tube comprising a plate, a second plate in parallel relation to said first plate, a supporting connection from said first plate to said second plate, parallel grid elements between said plates, a cathode between said grid elements, a single vertical arbor substantially coextensive with said electrodes, and supporting connections from said arbor to said electrodes.
9. A vacuum tube device comprising a press, an M-shaped filamentary cathode, an arbor substantially coextensive with said cathode extending from said press supporting wires extending from said press to the base of said cathode, supporting wires extending from said arbor to said cathode, and means for passing current serially through said cathode.
10. A vacuum tube device comprising a glass arbor, an M-shaped filamentary cathode extending in a plane parallel to and outside of said arbor, said filament being substantially coextensive with said arbor and supported thereby, and means for passing current serially through said cathode.
11. A vacuum tube device comprising a glass arbor, an M-shaped filamentary cathode extending in a plane parallel to and outside of said arbor, said cathode being substantially coextensive with said arbor and supported thereby, and another electrode supported from said arbor.
12. A grid electrode for vacuum tubes comprising two U-shaped frames and a member of conductive material connected from one frame to the other.
13. A grid electrode for vacuum tubes comprising two U-shaped frames and a plurality of parallel members connecting said frames.
14. In combination, a pair of parallel plate anode members, and a grid electrode comprising a pair of U-shaped frames disposed adjacent the edges of said plates and at right angles thereto, and a member connecting said U-shaped frames.
15. A vacuum tube device comprising anode surfaces, a cathode, and a double grid electrode having a plurality of substantially parallel grid surfaces and a pair of frames, one on each side of the said cathode and each supporting one of said grid surfaces.
16. A vacuum tube device comprising anode surfaces, a cathode, and a double grid electrode having a plurality of substantially parallel grid surfaces, a pair of frames, one on each side of said cathode and each supporting one of said grid surfaces and a support for suspending said cathode between said frames.
- In witness whereof I hereunto subscribe my name this 15th day of January, A. D. 1919.
- HAROLD D. ARNOLD.
